LOCK.

1,316,177.

Specification of Letters Patent. Patented Sept. 16, 1919.

Application filed May 3, 1916. Serial No. 95,229.

To all whom it may concern:

Be it known that I, ALBERT A. PAGE, a citizen of the United States, residing in East Haven, in the county of New Haven and State of Connecticut, have invented certain new and useful Improvements in Locks, of which the following is a full, clear, and exact description.

This invention relates to locks, and more particularly to locks of the mortise type intended to be applied to metal doors. The invention also refers especially to means for securing a mortise lock within a hollow metal door stile.

In applying mortise locks to hollow metal doors, considerable difficulty has been encountered heretofore by reason of the fact that the door stile usually has to have certain metal reinforcements to which the face plate or front of the lock is screwed or otherwise secured.

One of the objects of the present invention is to do away with the direct connection of the front or face plate of the lock to the door stile and thereby obviate the necessity of inserting one or more metal plates within the stile.

The invention has also in view the general improvement and simplification of the construction, whereby the application of the lock to the door is considerably facilitated.

To these and other ends, the invention consists in the novel features and combinations of parts to be hereinafter described and claimed.

In the accompanying drawing,

Figure 1 is a fragmentary outside view of a metal door equipped with my improvements;

Fig. 2 is an edge view of the door;

Fig. 3 is a view of the door stile, looking from the inside of the room;

Figs. 4, 5 and 6 are sections on lines 4-4 (Fig. 1), 5-5 and 6-6 (Fig. 3) respectively;

Fig. 7 is a detail perspective view of the upper portion of the mortise lock case; and

Fig. 8 is a detail view of the outside lever handle escutcheon.

In the drawing, I have shown my improvements applied to a metal door having a hollow stile 10 which, in accordance with the usual practice, is formed as a metal tube of generally rectangular cross-section. At the edge of the door, the stile is provided

with an elongated slot 11 to receive the face plate or front 12 of a mortise lock 13 housed within the stile. The slot 11 extends completely through the wall of the metal tube and corresponds closely in contour with the face plate 12 which fits snugly in said slot with its outer face substantially flush with the outer face of the metal tube. The particular thickness of the face plate 12 relatively to the thickness of the tube wall is not material; in the example illustrated, the wall of the tube is somewhat thinner than the face plate, as shown, for example, in Fig. 5. The face plate is not directly connected with the tube in any way and need not be, because the mortise lock 13 is securely fixed in the tube with the face plate in the proper position in its slot in the following manner: At the upper part of the case of the mortise lock 13 is an upwardly projecting lug 14, which is preferably cast on the main body portion 13^a of the lock case and independent of the cap plate 13^b, as shown in Fig. 7. Preferably this lug 14 is of the same thickness as the lock case, one face of said lug being flush with the cap plate, and the opposite surface of said lug being flush with the back of the lock. A bore or perforation 15 extends through the lug 14 and is adapted to receive an attaching screw 16 passing transversely through the metal tube. At a point opposite the opening 15 of lug 14, the tube 10 is provided at the outside of the door with an opening 17 (Fig. 4), in which a button 18 is fitted, said button having a flange 18^a overlying the rim of the opening 17. The button has an inwardly projecting socket 19 provided with interior screw threads. At the inner side of the door, a button 20, somewhat similar to the button 18, is fitted in an opening 21 opposite the lug perforation 15, and this button 20 is provided with an inwardly extending socket and with a bore extending entirely through the button and adapted to accommodate the fastening screw 16 previously mentioned. Suitable means, such as a pin 22, are provided for preventing the rotation of the button 18 in the tube wall. This button presents a socket or sleeve 19, which is internally threaded, and which is adapted to abut one side face of the lug 14, whereas the button 20 has a socket or sleeve portion which is smooth inside, the sleeve being adapted to abut the lug 14 at the corresponding side.

The screw 16 has threads 16^a at its inner end adapted to engage the threads of the sleeve 19, and when the screw is screwed into said sleeve, the mortise lock will be tightly 5 clamped in position between the sleeves and between the opposite walls of the metal tube. By having the sleeves of the two buttons 18, 20 of the same depth, and clamping said sleeves against opposite surfaces of the lug 10 14, and clamping the flanges of said buttons against opposite surfaces of the tube, as described, the mortise lock can be securely clamped in a position centrally of the tube, as will be understood.

15 Means are provided for securing the lock in the tube at the bottom of the lock as well as at the top, and the bottom securing means is somewhat similar to the top securing means, although in this case the spacing sleeves are formed on the inside and outside escutcheons 23, 24 respectively. In the example selected for illustration, the mortise lock is provided with a latch bolt 25 adapted to be retracted by inside and 20 outside lever handles 26, 27, and the escutcheons 23, 24 serve as mountings for the respective lever handles. The outside escutcheon 24 is provided at the upper end with a perforation through which a screw 28 is screwed into the outer wall of the metal tube 10, as shown in Figs. 1 and 5. Similarly, the inside escutcheon 23 is provided at the upper end with an opening 25 through which a screw 29 is screwed into the inner wall of the tube, as shown in Figs. 3 and 5. At the lower end of the escutcheon 24, the same is provided with an inwardly extending sleeve 30, which engages an opening in the wall of the tube 30 35 and projects inwardly into engagement with the face of the lug 14^a at the bottom of the mortise lock, said sleeve being internally threaded and corresponding substantially with the sleeve 19 of the button 40 45 18, previously described. At the lower end of the inside escutcheon 23, the same is provided with a perforated sleeve 31 generally similar to the button or sleeve member 20, and a screw 16^b similar to the screw 50 55 16^a is passed through the sleeve 31 and lug 14^a into the threaded sleeve 30 for screwing the parts together substantially in the manner previously described.

In the particular example shown, the latch bolt 25 may be retracted by a cylinder lock 32 passing through an opening in the outer wall of the metal tube and secured in the mortise lock in the usual manner.

It will be seen that by the construction 60 described, the mortise lock may be very readily mounted. It is first fitted into place in the metal tube with its face plate lying in the slot of the tube substantially flush with the tube surface at the edge of the door, and the parts carrying the spac-

ing sleeves are then applied, and the fastening screws 16, 16^b screwed into place. The escutcheons 23, 24 are also secured to the metal tube (but not to the lock) by the screws 29, 28. It is obvious that although 70 the screw 28 can be removed from the outside of the lock, the lock cannot be attacked in this way, because the outside escutcheon 24 will still be held in place at two points, *i. e.*, where its centering sleeve 24^a (Fig. 8) 75 fits an opening in the tube wall, and where its sleeve 30 engages a similar opening. The heads of the screw 16, 16^b are of course located at the inside of the door and are not accessible from the outside. 80

Without limiting myself to the precise construction shown, I claim:

1. In a lock for metal doors, the combination of a hollow metal stile of substantially rectangular cross-section having an elongated slot in one wall, a mortise lock in said stile having its face plate set in said slot but free from the stile, the side walls of the lock case being spaced from the opposing side walls of the stile, said last 90 named side walls having aligned openings therein, sleeve members extending through said openings and abutting the mortise lock case at opposite sides and having portions overlying the edges of the openings in the 95 side walls of the stile, and a fastening member interconnecting said sleeve members.

2. In a lock for metal doors, the combination of a hollow metal stile of substantially rectangular cross-section, a mortise lock case in said stile and having its side walls spaced from the opposing side walls of the stile, the latter side walls being provided with upper and lower perforations, the perforations of one side wall of the 100 stile registering with those of the other side wall, spacing sleeves extending through said perforations into engagement with the sides of the lock case at the upper and lower portions of said case, and screws 105 connecting the opposing sleeves for holding the parts in assembled relation.

3. In a lock for metal doors, the combination of a hollow metal stile of substantially rectangular cross-section having a slot 115 in the wall at the edge of the door, a mortise lock case in said stile having a face plate located in said slot, said face plate carried by said case but free from the stile, the side walls of the lock case being spaced from the opposing side walls of the stile, and means coöoperating with the upper and lower portions of the lock case for holding it in place in the stile.

4. In a lock for metal doors, the combination of a hollow metal stile of substantially rectangular cross-section having a slot in the wall at the edge of the door, a mortise lock case in said stile having a face plate located in said slot, said face plate 125 130

- carried by said case but free from the stile, the side walls of the lock case being spaced from the opposing side walls of the stile, and means coöperating with the upper and lower portions of the lock case for holding it in place in the stile, said means including flanged sleeve members resting against the outer faces of the side walls of the stile and against the outer side faces of the lock case.
5. The combination of a hollow stile member, a mortise lock fitted therein and having a perforated lug, spacing sleeves on opposite sides of the stile adapted to engage said lug, and a fastening screw passing through one of said sleeves and through the lug into the other sleeve; substantially as described.
10. The combination of a hollow stile member having a slot at the edge of the door, a mortise lock housed within said stile member and having a face plate lying in said slot, lugs projecting from said mortise lock at the upper and lower portions thereof respectively, and fastening members extending transversely across the stile and passing through said lugs; substantially as described.
15. The combination of a hollow stile member of substantially rectangular cross-section having a slot at the edge of the door, a mortise lock fitted within said hollow stile member with its face plate lying in said slot, the side walls of said lock spaced from the inside and outside walls of the hollow stile member, said inside and outside walls provided with perforations, sleeve members extending through said perforations and having lateral flanges overlying the edges of said perforations, and a fastening member interconnecting said sleeve members and passing through a portion of said mortise lock; substantially as described.
20. The combination of a hollow stile member of substantially rectangular cross-section having a slot at the edge of the door, of a mortise lock housed within said stile member and having a face plate located in said slot but separate from the stile member, the inside and outside walls of said stile member having openings therein, members engaging said openings and extending inward into the stile and into substantial abutment with opposite faces of the mortise lock case, and a fastening member interconnecting said last-named members; substantially as described.
25. A mortise lock having a case and a face plate, said case composed of a body portion and a cap, and a lug integral with the body portion of said case at one end and of substantially the same thickness as the lock case, said lug having a perforation extending therethrough; substantially as described.
30. A mortise lock having a case and a face plate, said case comprising a body portion and a cap, said body portion having a 65 perforated lug cast integral therewith at one end of the case, said lug having a side face substantially flush with the outer face of the cap and having another side face substantially flush with the back of the body 70 portion; substantially as described.
35. A mortise lock having a case and a face plate, said case composed of a body portion and cap, and vertically directed perforated lugs on the body portion at the 75 upper and lower parts thereof respectively, said lugs and case having substantially the same thickness; substantially as described.
40. The combination of a hollow metal stile member, a mortise lock fitted therein, 80 supporting plates applied to opposite faces of said stile at the outside and inside of the door respectively, means for interconnecting said plates and clamping them on the door, and means comprising projections on said 85 mortise lock and supporting plates for supporting said lock from said interconnecting means; substantially as described.
45. In a lock for doors, the combination of a hollow door, a mortise lock mounted 90 therein, a lug formed upon said lock and projecting therefrom, securing means extending through a side wall of said hollow door and through said lug for supporting said lock within said door and means upon 95 one face of said door provided with a projection extending inwardly through one of said walls to space said lock therefrom.
50. In combination with a door having a lock receiving opening therein, a mortise 100 lock mounted in said opening and having a face plate flush with the edge of said door, and means independent of said face plate for securing said lock within said opening, comprising a perforated lug formed upon 105 said lock and extending from an end thereof, flanged sleeves mounted in the oposite faces of said door engaging said lug, and securing means extending through said sleeves and lug; substantially as described.
55. In a lock for doors, the combination of a hollow door, a mortise lock mounted therein, securing means for fastening said lock within said hollow door in spaced relation to the walls thereof, comprising means 110 mounted upon one face of said door having projections extending through a wall of said door into abutting engagement with a lateral face of said lock, and bolts securing said lock rigidly in place within said door in engagement with said projections.
60. In witness whereof, I have hereunto set my hand on the 1st day of May, 1916.
- ALBERT A. PAGE.
